(57) **CLAIM**

What is claimed is the ornamental design for a glass door for outdoor oven, as shown and described.

DESCRIPTION

FIG. 1 is a front top isometric view of a glass door for outdoor oven showing Applicant's invention;

FIG. 2 is a bottom rear isometric view thereof;

FIG. 3 is a front elevation view thereof;

FIG. 4 is a left side view thereof;

FIG. 5 is a right side view thereof;

FIG. 6 is a top view thereof;

FIG. 7 is a bottom view thereof;

FIG. 8 is a rear elevation view thereof; and,

FIG. 9 is a front elevation view of the glass door for outdoor oven shown in an exemplary oven environment.

The broken lines showing portions of the article and environment form no part of the claimed design.
